UNITED STATES PATENT OFFICE.

SAMUEL W. REYNOLDS, OF WEST TOLEDO, OHIO.

DESIGN FOR A HARNESS ORNAMENT.

No. 39,055.

Specification for Design

Patented Feb. 4, 1908.

Application filed April 24, 1906. Serial No. 313,519. Term of patent 14 years.

To all whom it may concern:

Be it known that I, SAMUEL W. REYNOLDS, of West Toledo, in the county of Lucas and State of Ohio, have invented a new, original, and ornamental Design for Harness Ornaments, reference being had to the accompanying drawings, forming part of this specification, in which

The figure is a plan view of a harness ornament embodying my design.

I claim:

The ornamental design for a harness ornament, as shown.

SAMUEL W. REYNOLDS.
